COMBINED FOOD TRAY, GLASS HOLDER AND ASH TRAY OR THE LIKE

John J. Labe, Temple, Pa.

Application July 28, 1958, Serial No. 51,954

Term of patent 14 years

(Cl. D44—10)

Fig. 1.

Fig. 2.

Fig. 3.

Fig. 1 is a perspective view of a combined food tray, glass holder and ash tray showing my new design.

Fig. 2 is a similar but exploded view showing the separate, attachable parts of Fig. 1, and

Fig. 3 is a perspective, bottom view of the food tray and clamp shown in Figs. 1 and 2.

I claim:

The ornamental design for a combined food tray, glass holder and ash tray or the like, substantially as shown.
